JACK B. CHAMBERS, OF HOUSTON, TEXAS, ASSIGNOR TO CALIFORNIA CORRUGATED CULVERT COMPANY, OF WEST BERKELEY, CALIFORNIA, A CORPORATION OF CALIFORNIA

METALLIC CULVERT

Application filed March 2, 1927. Serial No. 171,991.

This invention relates generally to methods and means for reinforcing the ends of metallic culverts. It has special application to metallic culverts of the corrugated type, although certain features of this invention are broadly applicable to a variety of metallic structures which are cylindrical in shape, such as drain pipes, water conveyors and the like.

10 Metallic culverts such as are used for drainage of water under railroads or highways must be capable of withstanding severe loads, and in addition must be constructed so as to prevent deterioration. Culverts of this type 15 have been previously constructed of sheet metal such as galvanized iron, which is corrugated circumferentially and reinforced at the ends by metallic rods. These rods have been generally attached to the ends of the culverts by rolling them into the end corrugations, or in some instances a metal band has been secured to the end of the culvert by means 20 of rivets or other such fastening devices. The chief difficulty with the first method has been 25 that suitable forming machines must be designed and constructed to bend the ends of the sheet metal about the reinforcing rod. This bending is especially detrimental to the sheet where galvanizing is employed, particularly where the culvert is relatively small 30 in diameter since the sharp bending breaks and chips off the galvanizing. In addition to requiring special forming machines this method also requires special dies for notching 35 the ends of the corrugated sheets before they are rolled upon the rods. Riveting the reinforcing bands to the culvert is also an expensive manufacturing method as it necessitates the use of special machinery for 40 punching the culvert sheet and the reinforcing bands. Furthermore this method does not give uniform reinforcing of the culvert since the band is only secured at spaced points.

45 It is an object of this invention to devise a reinforced metallic culvert which may be manufactured cheaply and with a minimum of machinery.

50 It is a further object of this invention to devise an end reinforcement for a galvanized

metal culvert which will not injure the galvanizing and which will permit the culvert to retain its original form.

It is a further object of this invention to increase the conveying capacity of a metal 55 culvert.

Further objects of this invention will appear from the following description in which I have set forth the preferred embodiment 60 of my invention. It is to be understood that the appended claims are to be accorded a range of equivalents consistent with the state of the prior art.

Referring to the drawing:

Fig. 1 is a side elevational view showing 65 the end of a metallic culvert incorporating the principles of this invention.

Fig. 2 is a view similar to Fig. 1 but showing a modified form of reinforcement.

Fig. 3 is a view similar to Fig. 1 showing a 70 reinforcement combined with a bell shaped orifice.

Fig. 4 is a view showing a modification of the structure shown in Fig. 3.

The invention as disclosed in the drawing 75 includes a sheet metal culvert 10 which is cylindrical in shape and is provided with a series of circumferential corrugations 11. The end corrugation 12 has inner and outer curved peripheral surfaces 13 and 14, and seated against the inner peripheral surface 13 there is a metallic rod or band 16. This metal band 16 has an outer peripheral surface 17 which is shaped so as to conform generally to the contour of the corrugations and 80 is seated against the inner peripheral surface 13 of corrugation 12. The rod 16 is preferably a continuous band which is circular in shape, and may be manufactured of a rod bent to form a circle of the required diameter and having its ends welded together.

In constructing a reinforcement of the kind described above, the reinforcing rod 16 is first formed of the correct diameter. The edge of the corrugation 12 is then expanded 85 by suitable machinery to permit insertion of rod 16, after which the corrugation 12 is then clinched down around the rod to approximately its original form. The slight amount of bending of the sheet metal required by 90

this operation will not break off the galvanizing, even if the culvert is relatively small in diameter. In practice both ends of a culvert are reinforced in this manner although in some instances only one end may be reinforced.

Instead of seating the reinforcing rod upon the inner peripheral surface 13 of the end corrugation, it may be also seated against the outer convex peripheral portion 214 as shown in Fig. 2. In this case the reinforcing rod 216 has an inner peripheral surface 217 which is curved to correspond generally to contour of the culvert corrugations. In the manufacture of the reinforcement of this kind the end corrugation is first contracted and the reinforcing rod slipped over the end thereof, after which the end corrugation is then expanded to fit snugly against the peripheral surface 217.

In Fig. 3 I have shown a reinforcing rod similar to that shown in Fig. 2 which is combined with a transition member for increasing the capacity of the culvert. Thus formed integral with the reinforcing rod 316 there is a bell mouthed member 20 which extends beyond the end of the culvert. In this case the inner peripheral surface of reinforcing rod 316 engages the outer peripheral surface of the end corrugation. However the outer peripheral surface of the rod may also engage the end corrugation similar to the construction shown in Fig. 1. A combined reinforcement and transition member of this kind is shown in Fig. 4 in which member 21 is formed integral with the reinforcing rod 416. The bell mouthed members 20 and 21 are seamless and serve as additional reinforcement and to aid flow of water into and out of the culvert unit. These members may be formed integral with the rod or welded thereto.

In its preferred form the reinforcing rod is retained upon the last corrugation by abutting contacts only. This construction is desirable not only because of its extreme simplicity, but because it is better able to resist rust and corrosion.

It will be obvious that the culvert which I have provided may be readily manufactured with simple machinery. Sharp bending of the sheet metal is avoided so that the galvanizing is not injured and the ends of the culvert will resist rust and corrosion as well as the other parts. At the same time the reinforcing action may be made superior to prior reinforcements, since the rod may be made heavier than is practical in other methods.

I claim:

1. A sheet metal culvert unit of the corrugated type having an endless reinforcing metal bar interfitting an end corrugation only, one peripheral surface of the bar corresponding generally to the contour of the culvert corrugations.
2. A unitary article of manufacture com-

prising a sheet metal culvert of the corrugated type having an endless reinforcing bar on an end corrugation only of each end of the same, said bar having a peripheral surface corresponding generally to the corrugations of the culvert.

3. A unitary article of manufacture comprising a metal culvert having circumferential corrugations, and an endless metal reinforcing bar having a peripheral surface abutting the peripheral surface of an end corrugation only.

4. A unitary article of manufacture comprising a metal culvert having circumferential corrugations, and an endless metal reinforcing bar having a peripheral surface interfitting and abutting the peripheral surface of only an end corrugation, said bar being retained upon the culvert by abutting contacts only.

5. A unitary article of manufacture comprising a metal culvert having circumferential corrugations, an end corrugation corresponding generally to the other corrugations of the culvert, and an endless metal reinforcing band having a peripheral surface engaging only one periphery of said end corrugation, said band being retained in position by abutting contacts only.

6. A unitary article of manufacture comprising a sheet metal culvert having circumferential reinforcing corrugations, a seamless metal band having a curved peripheral surface interfitting one of the end corrugations, said end corrugation being formed to fit said band but having substantially the same form as the other corrugations of the culvert, and an integral bell-shaped member extending from one edge of said band, said member being of seamless construction.

In testimony whereof, I have hereunto set my hand.

JACK B. CHAMBERS.
